[57] CLAIM

The ornamental design for a combined comb and scalp massage bottle, as shown and described.

DESCRIPTION

FIG. 1 is a front elevational view of a combined comb and scalp massage bottle showing my new design, the rear view being a mirror image;

FIG. 2 is a right side elevational view thereof;

FIG. 3 is a left side elevational view thereof;

FIG. 4 is a top plan view thereof; and

FIG. 5 is a bottom plan view thereof.
